Primary Examiner—Caron Veynar*Assistant Examiner*—Mary Ann Calabrese(74) Attorney, Agent, or Firm—Sofer & Haroun, LLP(57) CLAIM

I claim the ornamental design for a pillow, as shown and described.

DESCRIPTION

FIG. 1 is a perspective view of the pillow in a relaxed configuration showing the new design; and

FIG. 2 is a reduced side view of the pillow of FIG. 1, shown in an alternate position of use mounted on a chair in accordance with the present invention; and,

FIG. 3 is an elevation view of the pillow of FIG. 1 in fully extended configuration, in accordance with the present invention.

The dashed portion showing the upper backrest portion of a chair in FIG. 2 is shown only to illustrate the position of the pillow on a chair and does not form any part of the claimed design.
